UNITED STATES PATENT OFFICE.

LOUIS NOEL, OF SPRINGFIELD, MASSACHUSETTS, ASSIGNOR OF ONE-HALF
TO HENRY BLODGETT, OF LUDLOW, MASSACHUSETTS.

BICYCLE-BELL.

SPECIFICATION forming part of Letters Patent No. 610,495, dated September 6, 1898.

Application filed October 12, 1897. Serial No. 654,936. (No model.)

To all whom it may concern:

Be it known that I, LOUIS NOEL, a citizen of the United States, and a resident of Springfield, (Indian Orchard,) in the county of 5 Hampden and State of Massachusetts, have invented certain new and useful Improvements in Alarm-Bells for Bicycles, of which the following is a specification.

This invention relates to an improvement 10 in alarm-bells for bicycles of the class in which the bell is mounted on a movable support together with a roller, so that when said support is moved and the roller placed in frictional engagement with the tire of the running wheel of the bicycle it will cause a repeated sounding of the bell.

The invention consists of constructions and combinations of parts to constitute the improvements, all substantially as will herein- 20 after appear, and be set forth in the claims.

The invention is fully and clearly illustrated in the accompanying drawings, in which—

Figure 1 is a perspective view of the forward part or head portion of a bicycle, showing the improved alarm-bell and its actuating devices mounted for operation thereon. Fig. 25 2 is a plan view and partial horizontal section of the alarm-bell appliances, the front fork-legs of the bicycle, on which the bell is mounted, being also shown in horizontal section.

Similar characters of reference indicate corresponding parts in both the views.

35 In the drawings, A represents a yoke or holder of stirrup form, having the clips a a, by which it is secured in place on the fork-legs b b of the bicycle, said yoke comprising the opposing forwardly and upwardly extended members 10 10, having the approached portions 12 12, which terminate in the upturned lugs 13 13.

40 B represents a stirrup or Y shaped frame, the same consisting of a single length of flat strip metal having its middle portion doubled on itself, as seen at 14, and having its forward separated extremities 15 15 arranged opposite each other to constitute the swinging support for the duplicate cup-shaped bells 45 C C and the wheel or roller D, which is arranged between them. The said bell-carry-

ing stirrup B is at 16 pivotally mounted between the said lugs 13 13 of the supporting-frame A, the pivotal connection being constituted by the screw d, on which the spiral springs f f are also connected and supported. These springs have their forward ends 18 engaged with the arms 15 15 of the stirrup-frame B, their opposite ends, as seen at 19, being engaged with the yoke-frame A, all 55 whereby said springs exert an elevating and supporting force against the stirrup B, which carries the bells and the actuating-roller D.

G represents a sleeve or journal-shaft, on the middle of which the extended hub g of the 60 roller D is mounted for rotation. The bells are of hemispherical or dish form, having the thickened hub or central portions 20, which set against the ends of the said journal-sleeve, and the screws h h are passed through the 65 stirrup members 15 15, through the bell-hubs, and with a screw engagement into the opposite ends of the said journal-sleeve G.

The roller, of which the extended hub g is 70 in the center, has the median web or flange g², with the edge rim g³, of trough shape, receiving therein the rubber ring g⁴, the same being secured by cementing.

Each bell has an inwardly-extending rib or projection i, and the median web g² of the 75 roller has the laterally-extended spiral springs j, the same being suitably secured to said web, and each carries at its outer end a ball or knob j², which serves as a striker by coming, as the roller D is rotated successively against 80 the bell projection i. The springs on which the knobs are fixed permit the knobs to yield, so that the striker may readily pass the bell projection after striking it.

M represents a hand-operated lever mounted to swing on the clip m, which is secured on the handle-bar, and n represents the connecting-rod which unites the lever m with the rear arm of the bell and roll carrying stirrup B. This connecting-rod is constructed 90 extensible and contractible by being made in two lengths 22 22, both of which have sliding engagement through the sleeve 23 and which are held as an integral rod by the binding-screw 24. This extensible connecting-rod, 95 while involving in itself no novelty, is advantageously employed to enable the bell-actuat-

ing device to be adjusted on bicycles having any height of head or any desired elevation of handle-bar.

It will be noted that the journal-sleeve G is 5 slightly longer than the hub *g* of the roller D and that the screws *h h* bind the bell-hubs 20 firmly against the ends of the sleeve and prevent the bells rotating, while the roller is free to rotate relatively to the bells.

10 By providing two cup-shaped bells at opposite sides of the roller, with their projections to be struck in opposition, a full detonation of each bell may be had alternately in quick succession.

15 As manifest, the swinging of the lever *m* will impart a rising movement to the connecting-rod *n* and a downswinging of the roller onto the tire E of the bicycle-wheel, the rolling movement, through the strikers *j j*, sounding the bell in quick succession so long as the roller is purposely retained in contact against the tire of the wheel.

20 The present construction of bicycle alarm-bell and operating appliances therefor may 25 be mounted adjacent the rear wheel, obviously, as may be preferred by some riders, in lieu of having its location at the front of the bicycle, substantially the same or any equivalent operating means being provided 30 to swing the movable support B into greater proximity to the tire.

I claim—

1. In an alarm-bell for bicycles, the combination with the stirrup-shaped support B, 35 and means for pivotally supporting it on the bicycle, adjacent the wheel thereof, of the duplicated dish-shaped bells provided with the internal projections *i* and having the central internal hubs 20, and the journal- 40 shaft, the bells being arranged in opposition with their hubs against the ends of said journal-shaft, and all within the opposite members of the stirrup-support, the screws *h h* passed through the extremities of said 45 support, through the hub-provided portions of the bells, and with a screw engagement

into the ends of the journal-shaft, clamping said bells against said shaft ends, a sleeve-hub *g* loosely surrounding said journal-shaft and free to rotate thereon provided with the 50 central web or flange *g* between the edges of the bells and extended diametrically outward beyond the bells, and adapted for rolling bearing on the vehicle-wheel, said web-flange carrying the laterally and oppositely 55 extended springs provided at their free ends with the striker balls or knobs, and means for moving the stirrup-support toward and away from the bicycle-wheel, substantially as described.

2. In an alarm-bell for bicycles, a stirrup-support B consisting of a strip of flat metal having its middle portion 14 doubled on itself, and having its extremities 15, 15, spread, a yoke or holder A provided with the clips 65 *a a* and comprising the opposing forwardly and upwardly extended members 10 with the approached portions 12, 12, terminating in the upturned lugs 13, 13, between which the return-bent parts 14 of said stirrup-support 70 B are intermediately arranged, the screw-bolt *d* passed through said parts 13, 14, and constituting a pivot for the latter upon the former, the springs *f f* confined by said screw-bolt and having their extremities engaging 75 the stirrup for imparting an elevating pressure thereon, the bells or gongs supported immovably between said members 15, 15 and provided with the projections *i* the shaft G endwise held between the bells, and the roller 80 rotatable on the shaft, between the bells, and edgewise or diametrically extended therebeyond, and provided with the strikers, substantially as described and shown.

In testimony that I claim the foregoing as 85 my invention I have signed my name, in presence of two witnesses, this 25th day of September, 1897.

LOUIS NOEL.
